7 Claims

This invention pertains to a method of and apparatus for use in creasing textile material, in particular, garments made from such material and, for more specific example, men's trousers. This novel method and apparatus are functionally useful in creasing garments (such as trousers) made from conventional fabrics which are predominantly of natural fibers, such as wool, cotton, silk or mixtures thereof in forming creases which, although sharp and well-defined at first are not expected to remain indefinitely. However, the present invention is especially concerned with the treatment of textile material for the formation of permanent creases, for example, in the treatment of textile fabric comprising a substantial percentage of synthetic thermoplastic fibers, including stretch fabrics in which the stretch yarns are thermoplastic or of chemically treated cellulose fibers which exhibit thermoplastic properties, as well as those which have been chemically treated, for example, with resin, to make them wrinkle-resistant.

The creasing of trousers by the use of hot irons or by means of steam presses is still widely used. Proposals have also been made for creasing trousers, for example, by placing within each trouser leg a creasing device comprising crease-defining elements so arranged as to locate the creases and to tension the trouser leg from crease-to-crease, and then to subject the assembly to steam and pressure, or to baking heat within a cabinet or oven. However, none of such prior arrangements, so far as is known, has proven entirely satisfactory, in particular, because of the manner in which the heat is applied, it being recognized that the frequent exposure of an entire trouser leg of fine material, whether natural or synthetic, to the heat, moisture and pressure employed in creasing, has the cumulative effect of removing the original finish from the fabric and thus reducing its wear-resistance, and with respect to stretch fabrics, wherein the stretch yarns are thermoplastic, seriously reducing the stretch characteristics of the garment. Thus, for example, a stretch nylon denim comprising an all-cotton warp and 100% textured nylon filament filling may readily be creased simply by applying heat and pressure such that the memory of the nylon retains the crease rather than the coils or undulations which were initially imposed during the texturing of the yarn, but, when the heat and pressure are applied, in the manner customary in creasing trousers, the entire leg, as well as that part of the leg involved in the crease, loses the original stretch characteristics in whole or in part. In accordance with the present invention, wherein the heating effect is applied locally, only to the area where the crease is desired, loss of stretch in the garment as a whole is avoided.

The present invention has for its object the provision of a novel method of and apparatus such as to facilitate the forming of creases, either temporary or permanent, in textile fabric, including wrinkle-resistant and stretch fabrics, more especially in a trouser leg, with a minimum of damage to the material as a whole.

In the attainment of this object, the invention contemplates the use of apparatus comprising crease-defining elements so devised as themselves to apply heat either dry

2

or moist, so localized at those lines at which the creases are desired as substantially to avoid the heating of surrounding areas.

While the use of crease-defining elements which are otherwise heated is contemplated as within the purview of the invention, a preferred apparatus for use in the practice of the invention contemplates crease-defining elements which are electrically heated, for example crease-defining elements, each having embedded or housed therein in an electrical resistance unit to which current may be supplied from any suitable source, for example through a flexible conductor. The invention further contemplates the provision of means whereby the crease-defining element may supply moisture (either as water or steam) locally to the area to be creased as, for example, by providing the crease-defining element with absorbent material which may be moistened just prior to the use of the device, or by providing the crease-defining element with an internal chamber from which water or steam may be emitted during the actual creasing operation.

Other and further objects and advantages of the invention will be pointed out in the following more detailed description and by reference to the accompanying drawings wherein:

FIG. 1 is a side elevation of a creasing device according to one desirable embodiment of the invention;

FIG. 2 is an edge elevation of the device of FIG. 1;

FIG. 3 is a plan view of the device of FIG. 1, to somewhat larger scale;

FIG. 4 is a fragmentary section, to much larger scale, on the line 4—4 of FIG. 1;

FIG. 5 is a view generally similar to FIG. 4, but illustrating a modification;

FIG. 6 is a similar view but showing a further modification; and

FIG. 7 is a fragmentary, diagrammatic, transverse section through a trouser leg for illustrating what is here referred to as a "crease."

Referring to FIG. 7 of the drawings, there is diagrammatically illustrated what is commonly referred to (with reference to the creasing of the trouser leg) as a "crease" consisting, as shown, of a narrow fold comprising the plies F¹ and F² which converge at a very slight acute angle and which are integrally joined at J, whereas the parts M¹ and M² of the material, constituting the right and left main portions of the trouser leg, are widely spaced apart when the garment is worn.

A preferred form of the apparatus of the present invention is shown in side elevation in FIG. 1, this device comprising two like creasing elements 11 and 12 respectively, each here shown as of sheet material, for example stainless sheet steel and comprising the elongate body portions 14 and 14a respectively. These two creasing elements may be identical in all particulars.

As shown in FIG. 4, the material forming the creasing element has a bend at 15 where the body portion 14 merges with the creasing edge structure E¹ or E² (FIG. 2), this edge structure comprising two converging portions 16 and 17 which are integrally united to form a V-shaped structure about whose edge 18 the material to be creased is held under tension during the creasing operation. Preferably, as shown, the edge 18 is rounded to a small radius to avoid damage to the fabric being treated. As illustrated in FIG. 4, the side walls 16 and 17 of the creasing edge structure, which converge at an acute angle, for example 40°, define between them a vertically elongate chamber B within which there is arranged an elongate block 19 of material, desirably of electrical insulating character, for example porcelain, this block 19 having an internal chamber within which there is arranged an electrical heating unit of conventional type extending substantially from end-to-end of the element (here

55
60
65
70

shown as comprising resistance elements 20 and 21), these resistance elements being connected, at the upper end of the device, as illustrated in FIG. 1, to a flexible conductor 22 which may lead to any suitable source of electrical energy. As shown in FIG. 4, the block 19 is held in position within the V-shaped edge structure by means of a closure plate or bracket 23 which may, for example, be welded or otherwise secured to the side members 16 and 17 of the edge structure. It will be understood that the heating unit within the edge structure E² of the creasing element 11 will be connected as by a conductor, as shown at 23a, to a suitable source of electrical energy.

The creasing element 12 is provided at its upper end with an elongate connector 24 (FIGS. 1 and 2), desirably integral with the body portion 14 and which is substantially perpendicular to the edge 18 and provided with an elongate slot.

The other creasing element 11 is provided with a like connector 24a also having an elongate slot which is indicated at 26 (FIG. 1). At the lower end of the member 12 there is a connector 25 and at the lower end of the creasing element 11 there is an elongate connector 25a. These members 25 and 25a are provided with elongate slots which receive a bolt 28 provided with a wing nut, while the slots in the parts 24 and 24a likewise receive a bolt 29 provided with a wing nut. By this arrangement the upper ends of the parts 11 and 12 may be adjusted toward and from each other and secured in adjusted position by tightening the wing nut and in the same way the lower ends of the parts 11 and 12 are adjustable toward and from each other and held in adjusted position by the wing nut on the bolt 28. As will be noted by inspection of FIG. 2, the parts 11 and 12, when assembled, are of such shape, in plan, that the crease-defining edges 18 and 18a of the edge structures E¹ and E², respectively, are in the same vertical plane when the parts are assembled. For supporting the apparatus when in use, one or both of the creasing elements is provided with an apertured suspension device 30 (FIG. 2).

When the device is to be used for creasing a trouser leg, it is desirable to adjust the members 11 and 12 so that the edges 18 and 18a converge downwardly to a slight extent (as shown in FIG. 1) according to the taper of a trouser leg. Before using the device, the parts 11 and 12 should be so relatively adjusted that when the device is pushed down into a trouser leg the material of the trouser leg will be drawn tautly about the edges 18 and 18a by the simple act of forcing of the device down into the trouser leg. The tension to which the fabric is thus subjected, causes the fabric to press firmly against the creasing edge structures.

When the device is thus positioned, the heating units in the two edge structures E¹ and E² will be supplied with current so that the edge structures are heated. Desirably (although not here shown), provision may be made, as by the employment of a conventional thermostat, whereby the crease-defining edge structures may be held at that predetermined temperature which is required for setting the crease in the particular textile material being employed. With the creasing edges at the predetermined temperature, the device may be suspended by the use of the hanger 30 and allowed to remain in this situation for such a period of time as has been determined requisite to set the crease.

It will be noted that, with this apparatus, only that portion of the trouser leg which is to form the crease is subjected to the crease-setting temperature.

In using the device, as above described, it may be desirable, before or after placing the trouser leg on the device, to moisten that portion of the trouser leg which is to be creased, as by the use of a wet sponge. However, a modification of the device, as shown in FIG. 5, provides for locally moistening this particular part of the trouser leg concomitantly with the operation of setting

the crease. For this purpose the edge structure is provided with a pad P, for example, of sponge or foam rubber or plastic which may be secured to the edge structure in any desired manner, for example, by a suitable adhesive, and which may be moistened before introducing the device into the trouser leg, so that, as the creasing device is heated, vapor or steam will be evolved and directly moisten that part of the trouser leg, only, which is to be creased.

In a further modification, as shown in FIG. 6, the structure is generally similar to that of FIG. 4, but the block 19 is provided with an internal chamber 32 to which liquid may be supplied in any desired manner and from which small ports 33 extend outwardly through the walls 16 and 17 of the edge structure. Thus, by supplying the chamber 32 with water before the start of the operation, that part, only, of the trouser leg which is to be creased may be moistened while the creasing operation is being performed.

While the slot and bolt arrangement here shown, as a means for varying the width of the device, is simple, easy to manipulate and cheap to manufacture, it is contemplated, as within the purview of the invention, that other means, including springs or toggles might be employed in substitution for the slot and bolt arrangement. Likewise, instead of internal heating means, the apparatus could be used effectively by suspending it in a high-frequency electrical field whereby the metallic edge structures E¹ and E² could quickly be raised to the desired temperature.

As above suggested, the apparatus here disclosed is of notable utility in the creasing of material which has been pretreated to make it wrinkle-resistant. For example, a 50% polyester-50% cotton fabric treated with a resinous or cellulose reactant formulation of the delayed cure type may be cut and made up into a pair of slacks but not pressed. Then, instead of pressing creases into the legs of the garment, a creasing apparatus, such as that herein disclosed, would be introduced into each leg of the garment, after having been adjusted, so that in introducing the device the material of the garment leg would be drawn snugly about the creasing edges. Heat would then be supplied, as above suggested, so as to raise the several creasing elements to a temperature which, in the specific example just referred to, should be approximately 330° F. and this temperature should be maintained for approximately 15 minutes.

During this curing operation the fabric shrinks and thus tightens itself firmly about the creasing edge structures E¹ and E² and at the same time resin or reactant formulation cross-links with the cellulose portion of the fabric. Likewise, garments of stretch fabric may be permanently creased without damage to the uncreased portions.

At the completion of the treatment the creasing apparatus is removed from each of the garment legs, thus leaving a permanently creased garment but without the use of pressing or other customary procedures for forming the creases. It is understood, of course, that in accordance with the particular substances employed for making the fabric wrinkle-resistant and in accordance with the material of the fabric itself, various times and temperatures would be required all within the skill of those conversant with the art to insure permanence of the creases.

While certain desirable embodiments of the invention have herein been described and illustrated by way of example, it is to be understood that the invention is broadly inclusive of any and all modifications falling within the scope of the appended claims.

I claim:

1. Apparatus for creasing textile fabric comprising a creasing element of sheet material having converging portions which are joined to form a V-shaped edge structure, heating means located within said V-shaped edge structure, means whereby the textile fabric may be held in contact with said edge structure, and means whereby

moisture may be applied to that portion, only, of the material which contacts said edge structure.

2. Creasing apparatus for use in creasing a trouser leg, said apparatus comprising a pair of creasing elements, each having a V-shaped crease-defining edge structure, means for heating the crease-defining edge, only, of each of said elements, and means so connecting said elements that said edges may be relatively adjusted to a taper such that when the apparatus is introduced into a trouser leg, the material of the trouser leg will be strained tautly about said respective edges.

3. Apparatus according to claim 2, further characterized in that each of said creasing elements houses an electrical heating unit extending substantially from one end to the other of the respective creasing elements, and means for supplying electrical current to each of said heating units.

4. Apparatus according to claim 2, further characterized in that the connecting means for unitizing the creasing elements is so devised that the distance between the 20 crease-defining edges may be varied independently at opposite ends of the apparatus.

5. Apparatus according to claim 2, further characterized in having means associated with each respective crease-defining edge structure for supplying moisture to the material of the trouser's leg while held taut about said edge structure.

10

15

25

6. Apparatus according to claim 5, wherein the means for supplying moisture comprises a pad of absorbent material constituting the effective outer surface of the V-shaped edge structure.

7. Apparatus according to claim 5, further characterized in that for supplying moisture to the material held tensioned about said V-shaped edge structures, each of said V-shaped edge structures has a chamber for a moistening liquid, and each V-shaped edge structure is provided with escape ports through which moistening liquid may pass from the conduit outwardly into direct contact with the trouser leg material which is held taut about the crease-defining edge structures.
